CLAIM

The ornamental design for a watch, as shown and described.

DESCRIPTION

FIG. 1 is a front perspective view of a watch showing my new design with a watch case in a first position in a watch housing, showing a first watch face on the watch case and its elements and structures;

FIG. 2 is a bottom view thereof;

FIG. 3 is a top view thereof;

FIG. 4 is a left side view thereof;

FIG. 5 is a right side view thereof;

FIG. 6 is a front elevational view thereof;

FIG. 7 is a back elevational view thereof, exhibiting a back housing watch face;

FIG. 8 is a back perspective view thereof, exhibiting the back housing watch face;

FIG. 9 is a front perspective view of the watch showing my new design with a watch case in a second position in a watch housing, showing a second watch face on the watch case and its elements and structures;

FIG. 10 is a bottom view of the watch the watch case in the position of FIG. 9;

FIG. 11 is a top view of the watch the watch case in the position of FIG. 9;

FIG. 12 is a left side view the watch case in the position of FIG. 9;

FIG. 13 is a right side view the watch case in the position of FIG. 9;

FIG. 14 is a front elevational view the watch case in the position of FIG. 9;

FIG. 15 is a back elevational view the watch case in the position of FIG. 9, exhibiting the back housing watch face;

FIG. 16 is a back perspective view the watch case in the position of FIG. 9, exhibiting the back housing watch face;

(Continued)

FIG. 17 is a front elevational view of the watch with the watch case exhibiting the first watch face, the watch case in a third position in the watch housing to reveal an interior housing face;

FIG. 18 is a front elevational view of the watch with the watch case exhibiting the second watch face, the watch case in a fourth position in the watch housing to reveal the interior housing face;

FIG. 19 is a front perspective view of the watch showing the first watch face, with the watch case in a first rotational position in the watch housing;

FIG. 20 is a front perspective view of the watch showing the second watch face, with the watch case in a second rotational position in the watch housing;

FIG. 21 is a front perspective view of the watch showing the second watch face with the watch case in a third rotational position in the watch housing;

FIG. 22 is a front perspective view of the watch showing the second watch face with the watch case in a sliding position in the watch housing; and,

FIG. 23 is a front perspective view of the watch showing the second watch face with the watch case in the second position in the watch housing.

The broken lines in the drawings show environmental matter and are not part of the claimed design.
